WEED KILLER

Filed March 26, 1928

UNITED STATES PATENT OFFICE

WILLIAM H. BERGMANN, OF CLEVELAND, OHIO, ASSIGNOR TO THE AMERICAN FORK & HOE COMPANY, OF CLEVELAND, OHIO, A CORPORATION OF OHIO

WEED KILLER

Application filed March 26, 1928. Serial No. 264,642.

My invention relates to weed killers and more especially relates to the type of weed killer which deposits a charge of poisonous material at the severed portion of the roots of a weed.

An object of my invention is to provide a weed killer which cuts the roots and places a charge of weed killing material upon the freshly cut root of a weed.

10 Another object of my invention is to provide a weed killer wherein the poison will be deposited over a large surface of the freshly severed root of a weed.

Another object of my invention is to provide a device of the class described which may be quickly and easily recharged.

Another object of my invention is to provide a device of the class described which contains a minimum number of working parts, is simple to operate, durable in construction and inexpensive to manufacture.

These and other objects of my invention and the invention itself will become apparent from the following description, wherein reference is had to the accompanying drawings forming a part of this specification; of an embodiment of my invention.

Referring to the drawings:

Fig. 1 is an elevational view of an embodiment of my invention;

Fig. 2 is a side elevational view of the same;

Fig. 3 is a longitudinal medial sectional view of the fluid container and dispensing valve therefor;

Fig. 4 is an end view of the device of my invention; and

Fig. 5 is a transverse section taken on line 5—5 of Fig. 2.

40 Referring to the drawings wherein like parts are designated by like reference characters, at 1, I show a handle which may be made of wood or pipe and has a reduced end inserted in a socket 2 and may be held therein by bolts or rivets 3 running transversely through the socket and the handle. The socket terminates in a forging 4 which has a pair of integral saddles 5 extending from one side thereof and adapted to engage a cylindrical reservoir 6; the reservoir may be

fastened to the saddles by welding, brazing or riveting. The lower portion 7 of the forging is bent towards the reservoir beyond the lower end thereof, and the extremity is flattened at 8, to receive thereon a chisel shaped 55 blade 9 which is provided with a V-shaped cutting edge 10 at its extremity. The blade may be attached by its upper end to the forging by welding or riveting to the flattened end 8 of the forging.

60 The reservoir 6 is not necessarily cylindrical, but this form is preferred on account of the economy in construction. In the upper end of the reservoir is provided a plug or cap 11 which may be screw threaded or welded into the end of the reservoir, and has an upwardly extending drilled boss 12 centrally disposed thereon. There is also provided a filler hole 13 which may be closed by the 65 plug 14.

70 In the opposite end of the cylinder is disposed a dispensing valve mechanism, which comprises a plate having an upwardly extending annular flange which is screw threaded into the lower end of the cylinder. At 75 16 is provided an upwardly extending boss having a central bore 17 running axially therethrough and in axial alignment with the bore in the boss 12. The lower end of the bore connects with a coupling 18 having a passage 80 way 19 which receives a tube 20 soldered or welded in the coupling, which is held on the lower end of the dispensing valve by screws 21. A series of radial openings 26 are provided, disposed intermediate the ends of 85 the bore 17.

Upon the blade 9 and running longitudinally most of its length, welded or riveted thereto, is a rib 22 which may be of substantially triangular cross section and in the end 90 has a V-shaped notch which corresponds and aligns with the notch in the cutting end of the blade. A groove 23 runs the entire length of the rib opening towards the blade and provides a canal to receive the conduit or tube 95 20 which extends downward to the apex of the notch and is plugged at its end. A series of holes are drilled from within the canal before the rib is placed on the blade so that the point of the drill provides small openings 24 in the 100

highest portions of the rib which communicate with openings in the conduit 20. At the upper end of the blade and running transversely across it and extending outwardly to one side is provided an arm 25 which may be fastened to the blade by riveting or welding.

At 27 is provided a plunger which fits slidably within the bore 17. The lower end thereof is slightly pointed as shown at 30. In the upper end of the plunger is screw threaded a rod 28 which extends through the bore and the boss 12 and runs upward along the side of the handle and has at its end a hook or grip 29. The rod is guided adjacent its free end by a guide 32 fastened to the handle.

The plunger is spring pressed into the bore 17 by a helical spring 31 which is disposed around and guided by the rod 28. The spring has a limited compression which prevents the plunger from being entirely withdrawn from the bore.

When it is desired to use my invention for the eradication of noxious weeds, the blade is placed against the root of the weed and is pressed into the ground and by pressure upon the arm 25 with the foot, the blade cuts the root; and the grip 29 is then pulled upward, which allows a small quantity of the fluid from the reservoir, used to poison the root, to enter the bore 17, by means of the radial intake openings 26, which connect with the reservoir. The handle 29 is then released and the spring 31 which bears against the upper end of the reservoir and against the end of the plunger forces the plunger into the bore, closing the intake holes and forcing a portion of the liquid out of the chamber 17, through the conduit 20 in the blade, and out of the orifices adjacent the cutting edge of the blade upon the portion of the root which has been severed and left in the ground after the cutting operation. The effect is to permit removal immediately of that part of the weed above the ground and to kill the root that is left in the ground.

The fluid ejection, comprising the spring pressed plunger 27, when released after the plunger has been preliminarily lifted to permit a quantity of fluid to enter the cylindrical bore 17, will force the fluid through the duct 20 with great pressure, depending upon the pressure of the spring 31 and this may very well be many hundreds of pounds per square inch, since the spring 21 may have a power of from 10 to 30 pounds and the plunger 27 and the bore in which it reciprocates may be of a diameter of perhaps only $\frac{1}{4}$ of an inch.

The application of this high pressure to the fluid in the duct 20 will serve to forcibly eject all dirt or other extraneous substances from the openings 24 which are disposed in the lateral wall of the duct, and directly above and adjacent to the apex 29 of the inverted V-shaped sharpened edge 10 of the blade 9.

The provision of the foot pressure bar 25

is especially advantageous as it permits easy directing of the blade to the proper point adjacent the roots, the easy forcing of the blade to the desired point to sever the roots and enables the operator to lift the rod 28 by the handle 29 against the considerable pressure of the spring 31. The latter effect permits use of a heavier spring and therefore secures a higher fluid pressure in the duct 20 to remedy clogging of the passages 75 than would otherwise be possible.

The reservoir may be filled with a fluid or the like by pouring it in the upper end through the filler hole 13.

Having thus described my invention in a specific embodiment, I am aware that numerous and extensive departures may be made from the embodiment herein illustrated and described, without departing from the spirit of my invention.

I claim:

1. In a weed cutting and root destroying device, an elongated cutting blade having a forwardly disposed notched cutting edge, a handle projecting upwardly from and supporting the blade, a fluid reservoir carried by the handle, a high pressure fluid ejecting element for the reservoir, means providing a discharge duct for the reservoir carried by the blade extending longitudinally of the blade provided with a laterally disposed discharge opening in its lower portions disposed adjacent to and above the apex of the notched cutting edge.

2. In a weed cutting and root destroying device, an elongated cutting blade having a forwardly disposed substantially inverted V-shaped chisel-type cutting edge, a handle projecting upwardly from and supporting the blade, a fluid reservoir carried by the handle, a high pressure fluid ejecting element for the reservoir carried by the blade extending longitudinally of the blade provided with a laterally disposed discharge opening in its lower portions so disposed adjacent to and above the apex of the cutting edge, that said openings will permit ejection of the fluid from the reservoir at high pressure on the lower side of the blade in the longitudinal central portion thereof so as to flow directly onto the upper portion of the root stock when said stock is severed by the projection of the blade obliquely into the ground.

3. In a weed cutting and root destroying device, an elongated cutting blade having a forwardly disposed notched cutting edge, a handle projecting upwardly from and supporting the blade, a fluid reservoir carried by the handle, a high pressure fluid ejecting element for the reservoir, means providing a discharge duct for the reservoir carried by the blade extending longitudinally of the blade provided with a laterally disposed discharge opening in its lower portions disposed adjacent to and above the apex of the

notched cutting edge, said device comprising a laterally extending arm disposed adjacent the non-cutting end of the blade for engagement by the foot of the operator for forcibly projecting the blade into the ground.

4. In a weed cutting and root destroying device, an elongated cutting blade having a forwardly disposed notched cutting edge, a handle projecting upwardly from and supporting the blade, a fluid reservoir carried by the handle, a high pressure fluid ejecting element for the reservoir, means providing a discharge duct for the reservoir carried by the blade extending longitudinally of the blade provided with a laterally disposed discharge opening in its lower portions disposed adjacent to and above the apex of the notched cutting edge, said device comprising a laterally extending arm disposed adjacent the non-cutting end of the blade for engagement by the foot of the operator for forcibly projecting the blade into the ground, and means for operating said fluid ejecting element comprising a spring pressed plunger and a rod projecting along the handle for retracting said plunger against the pressure of said spring by manual pulling of the rod at the handle end thereof, said spring adapted to restrain the plunger to effect forcible ejection of the fluid through the discharge duct.

5. In a weed cutting and root destroying device, a support for a blade, a blade on the support, a cutting edge on the blade adapted to be thrust into the ground, a fluid duct associated with the blade and extending to a point adjacent the cutting edge, the blade and duct being adapted to be forced into the earth, a discharge opening for the duct positioned to permit discharge of fluid from the duct in a direction transverse to the direction of movement of the duct when shoved into the ground whereby clogging of the discharge opening is prevented.

6. In a weed cutting and root destroying device, a blade support, an elongated cutting blade adapted to be shoved into the earth, a cutting edge on the lower end of the blade, a fluid duct on the blade arranged generally in the direction in which the blade is shoved into the ground and extending to a point adjacent the cutting edge, a discharge opening for the duct opening at an angle to the direction of movement of the duct when shoved into the earth, whereby clogging of the duct is prevented.

7. In a weed cutting and root destroying device, a blade support, an elongated cutting blade adapted to be shoved into the earth, a cutting edge on the lower end of the blade, a fluid duct on the blade arranged generally in the direction in which the blade is shoved into the ground and extending to a point adjacent the cutting edge, a discharge opening for the duct opening at an angle to the direction of movement of the duct when

shoved into the earth, whereby clogging of the duct is prevented, a fluid reservoir connected with the duct and a high pressure fluid ejecting means for the reservoir to force fluid therefrom into the duct.

8. In a weed cutting and root destroying device, a blade support, an elongated cutting blade adapted to be shoved into the earth, a cutting edge on the lower end of the blade, a fluid duct on the blade arranged generally in the direction in which the blade is shoved into the ground and extending to a point adjacent the cutting edge, a discharge opening for the duct opening at an angle to the direction of movement of the duct when shoved into the earth, whereby clogging of the duct is prevented, a fluid reservoir connected with the duct and a high pressure fluid ejecting means for the reservoir to force fluid therefrom into the duct, said means comprising a cylinder, a piston therefor, and a lateral port through the piston wall, the piston being adapted to be withdrawn beyond the port to permit fluid to enter the cylinder through the port and resilient means for forcing the piston into the cylinder to cover the port and put under pressure the fluid in the cylinder.

In testimony whereof I hereunto affix my signature this 15 day of March, 1928.

WILLIAM H. BERGMANN.
